(57) **CLAIM**

The ornamental design for an inverter controller for electric motors, as shown and described.

DESCRIPTION

FIG. 1 is a left-front perspective view of the inverter controller for electric motors according to my design;

FIG. 2 is a left side view thereof;

FIG. 3 is a top view thereof;

FIG. 4 is a bottom view thereof;

FIG. 5 is a right side view thereof;

FIG. 6 is a front view thereof; and,

FIG. 7 is a rear view thereof.

In the drawings, the broken lines are for the purpose of illustrating portions of the inverter controller for electric motors that form no part of the claimed design.

1 Claim, 4 Drawing Sheets
